ORCHARD HEATER

Howard H. Christensen, San Antonio, Tex., assignor to O'Keefe & Merritt Co., Los Angeles, Calif., a corporation of California

Application February 23, 1932, Serial No. 594,407

12 Claims. (Cl. 158—91)

This invention relates to a heater and relates more particularly to an orchard heater for protecting trees, fruit, crops, etc., against injury from frost or extreme cold. It is a general object 5 of the present invention to provide an orchard heater of the oil burning type that is particularly effective in the production of heat and that is practically smokeless.

The types of orchard heaters in general use 10 produce great quantities of smoke which is extremely undesirable as it soils the trees, fruit etc., and in localities where a large number of orchard heaters are used, this smoke sometimes becomes a public nuisance. A low grade of liquid hydro- 15 carbon fuel is usually employed in orchard heaters, and the production of excessive smoke is often due to the incomplete combustion of the fuel caused by the insufficient or improper admixture of air with the gases of combustion rising from 20 the surface of the burning fuel.

An object of this invention is to provide an orchard heater operable to effect substantially complete combustion of the fuel to produce a maximum amount of heat with little or no smoke.

25 It is another object of the invention to provide an orchard heater that embodies improved and particularly effective means for admitting air into the combustion chamber and for mixing the air with the gaseous volatilized fuel to provide for 30 its complete combustion.

It is another object of the invention to provide an orchard heater that will burn or operate efficiently for a long period of time with a minimum amount of attention and regulation.

35 It is another object of the invention to provide an orchard heater of the character mentioned that is extremely easy to clean of soot, etc., that may accumulate in the combustion chamber. In devices of this character there is a decided tendency for soot, carbon, etc., to accumulate in the 40 stack and on the parts adjacent the points where the air is admitted to the combustion chamber or stack. This accumulation of soot and like matter, often greatly impairs the efficiency of the 45 heaters, and the usual types of heaters must be taken apart after short periods of operation and the soot removed from the various parts. In accordance with the present invention, the soot, carbon, etc., that may accumulate at the points of 50 admission of the air may be easily and quickly removed or dislodged by lightly tapping or striking a certain part of the heater.

It is another object of the invention to provide 55 an orchard heater that is extremely simple and inexpensive of manufacture. The heater of the

present invention is formed of a minimum number of simple parts that may be constructed of sheet metal or other relatively inexpensive material.

It is another object of the invention to provide 5 an orchard heater of the character mentioned that may be easily and quickly taken apart or dismantled for cleaning, etc.

It is a further object of the invention to provide 10 an orchard heater that includes improved means for directing and circulating air in the fuel container where the initial combustion occurs.

Other objects and features of the invention will be best and more fully understood from the following detailed description of typical forms and 15 applications of the invention, throughout which description reference will be had to the accompanying drawings, in which:

Fig. 1 is a vertical detailed sectional view of the 20 heater provided by this invention. Fig. 2 is a horizontal detailed sectional view taken as indicated by line 2—2 on Fig. 1. Fig. 3 is an enlarged fragmentary horizontal sectional view taken substantially as indicated by line 3—3 on Fig. 1. Fig. 4 is an enlarged fragmentary horizontal sec- 25 tional view taken substantially as indicated by line 4—4 on Fig. 1. Fig. 5 is an enlarged fragmentary vertical or sectional view taken substantially as indicated by line 5—5 on Fig. 3 illustrating a portion of the corrugated section or 30 collar, and a portion of the baffle. Fig. 6 is a vertical detailed sectional view of the lower end portion of the heater, illustrating a modified form of air deflector.

The embodiment of the present invention ill- 35 istrated in Figs. 1 to 5 inclusive of the drawings, includes, generally, a fuel container 10, means 11 for admitting air into the container 10 and for circulating the air in the container, 40 a body or main stack 12 mounted on the fuel container 10 and providing a combustion chamber 13, and means 14 for admitting air into the combustion chamber 13 and for effecting the admixture of the air with the gases of combustion 45 arising from the burning fuel F.

The fuel container 10 is a hollow structure of suitable shape provided to hold the fuel F and to support the main stack 12 and the various other parts of the heater. In the particular case illustrated in the drawings, the container 10 is 50 of round horizontal cross section, and has a flat bottom 15 and flared sides 16. A reducer is provided on the upper end of the container 10 and has a cylindrical collar 17 at its upper end and a downwardly and outwardly flared apron 18 at 55

its lower end. The apron 18 seats on the upper edge of the fuel container 10. An annular lip or flange 19 may be provided on the lower end of the apron 18 to have a snug disengageable fit 5 with a cylindrical bead or flange 20 on the upper end of the container walls 16. The fuel container 10 is adapted to be filled with fuel to a line a short distance below the flange 20 and the fuel F is initially burned directly in the container 10 to generate or form the gases of combustion that are finally consumed within chamber 13.

The means 11 for admitting air into the fuel container 10 is variable or adjustable to compensate for various atmospheric conditions, 15 quality and quantity of the liquid fuel F, etc. The means 11 is operable to spread or diffuse the air admitted into the fuel container 10 to provide for the effective initial combustion or burning of the fuel. An air inlet and filling opening 21 is provided in the apron 18 and is surrounded by an outwardly projecting rim or flange 22. A cap or closure 23 is hinged to the flange 22. The closure 23 is normally in the closed position illustrated in the drawings, but is adapted to be swung open to permit the ready filling of the fuel into the container 10. An aperture or opening 24 is provided in the closure 23 to admit the air into the fuel container 10. The quantity of air admitted through the opening 24 is adapted to be varied 25 by means of a slide or gate 25. The gate 25 is adapted to extend various distances across the opening 24 and may be readily moved or adjusted to provide for the regulation of the supply of air to the fuel container 10. Guide ways 26 may be 30 provided on the closure 23 to slidably carry the gate 25.

The means 11 includes a grate plate or air baffle 27 to direct or spread the incoming air downwardly against and across the surface of the burning fuel F. The air baffle 27 is spaced inwardly from the inlet opening 21 and depends from the apron 18 to have its lower end portion submerged in the fuel F. In the embodiment of the invention being described, the upper end of the air baffle 27 is hinged or pivoted to the under side of the apron 18 as at 28. It is preferred to have the air baffle 27 inclined downwardly and inwardly toward or across the vertical center of the fuel reservoir 10. A float 29 is provided on the lower end of the air baffle 27 to support or partially support the lower end of the baffle on the fuel so that the baffle is disposed at a suitable angle at 45 all times. In the preferred construction, the air baffle 27 is channel shaped in transverse cross section and is disposed with its open side facing outwardly. The air baffle 27 directs the incoming air downwardly to impinge on the surface of the burning fuel F and effectively diffuses the air throughout the upper portion of the container 10 to provide for the proper initial combustion of the fuel F. It will be noted that the baffle 27 50 prevents the incoming air, admitted through the opening 21, from passing rapidly through the upper end of the container 10 and out through the collar 17.

The main stack 12 is supported above the fuel container 10 through the means 14, as will be subsequently described, and forms or provides the combustion chamber 13 which receives the gases of combustion from the container 10. The main stack 12 is an elongate tubular member with open ends. In the specific form of the invention illustrated in the drawings, the main stack 12 is cylindrical and of substantially uniform 65 configuration throughout its length. It is a fea-

ture of the present invention that the main stack 12 is of larger diameter than the collar 17 to provide a large combustion chamber 13 in which the gases of combustion may have ample room for expansion. Spaced circumferential beads 30 5 may be provided to lend rigidity to the main stack 12. The lower end of the main stack 12 is open to receive air and the gases of combustion from the fuel container 10. A reducer collar or reducer 31 is provided on the upper end of the main stack 12 to carry the upper stack 32. An upstanding cylindrical flange 33 is provided on the upper end of the reducer 31. The lower end of the stack 32 slidably or removably fits over the flange 33. The stack 32 is of considerably less 15 diameter than the combustion chamber 13 to insure the desired draft, and the reducer 31 forms a suitable roof or restriction at the upper end of the combustion chamber 13.

The means 14 for admitting air into the combustion chamber 13 and for effecting the proper admixture of air with the gases of combustion rising through the collar 17 is such that the gases of combustion are forced or caused to thoroughly mix with the incoming air so that they are fully 20 25 completely burned within the combustion chamber. The air entering the combustion chamber 13 may pass into the lower end of the chamber in any direction and thus provide for the effective distribution of flame within the 30 chamber 13, and the complete diffusion of combustion to provide great heat.

The means 14 includes a corrugated collar or tube 35 extending over the upper end of the collar 17 and projecting upwardly into the lower end 35 of the combustion chamber 13. In accordance with the broader aspects of the invention, the collar or tube 35 may be removably supported on the collar 17 in any suitable manner. In the particular instance illustrated in the drawings, the 40 lower end of the corrugated tube or collar 35 rests on an outwardly projecting circumferential bead 36 on the collar 17. In accordance with the invention, the collar or tube 35 is corrugated throughout its circumference and length. The 45 corrugations extend longitudinally of the tube 35 and are preferably flat sided. The corrugations are comparatively deep to have their inner vertical edges engaging the exterior of the collar 17 and to have their outer vertical edges engaging 50 the inner walls of the main stack 12.

The corrugations provide a plurality of outer passages 37 for passing air upwardly into the lower end of the main stack 12, and a plurality of inner passages 38 for passing the gases of 55 combustion upwardly into the lower end of the main stack. The tube or collar 35, corrugated in the manner illustrated in the drawings, provides a maximum amount of surface which may become heated by the uprising gases and that effectively heat the air flowing upwardly through the passages 37. This pre-heating of the air causes an initial expansion of the air before it enters the combustion chamber 13 so that it more readily mixes with the volatile combustible 60 gases.

It is an important feature of the present invention that the upper end of the corrugated tube 35 is perforated and shaped to allow the air to enter the combustion chamber in all directions. 70 V-shaped cuts 40 are provided in the upper end of the corrugated collar or tube 35 to provide the corrugations with points, as clearly illustrated in Fig. 5 of the drawings. In accordance with the broader principles of the invention, the open- 75

ings or perforations in the upper end portion of the corrugated collar 35 may be of any desired or suitable shape or proportions. In the particular case illustrated in the drawings, vertical slots 41 are provided between each of the successive corrugations of the collar. The slots 41 extend downwardly from the V shaped cuts 40 to points in approximate alignment with the lower end of the main stack 12. It will be apparent that the slots 41 and the V shaped cuts 40 form air passages which allow the incoming air to pass into the chamber 13 in any direction. The incoming air flows upwardly through the passages 37 provided by the corrugations and becomes heated through contact with the sides of the corrugations and through radiation from the corrugations so that it is heated and expanded before reaching the combustion chamber proper. The corrugated tube or collar 35 constitutes a connection between the fuel container 10 and the combustion chamber 13 that carries the gases of combustion upwardly into the chamber 13 and admits air into the chamber so that it is properly mixed with the gases. The inner spaces or passages 38 provided by the corrugations of the collar 35 pass the gases of combustion upwardly into the chamber 13. The lower ends of the passages 38 are preferably closed. The lower end portions 42 of the corrugations are split and bent or crimped inwardly to close the lower ends of the passages 38 as illustrated in Fig. 4 of the drawings. The crimped ends 42 may rather tightly abut the collar 17 to seal the lower ends of the inner passages 38.

The corrugated tube or collar 35 is formed of sheet metal or other material that is "flexible." By "flexible" I mean capable of vibrating, shaking or jarring. It is an important feature of the present invention that the collar is constructed so that it vibrates or shakes when tapped or struck. Soot or carbon that may accumulate in the passages 37 or 38 and the slots 41 may be easily dislodged by striking or tapping the corrugated collar 35 to cause it to vibrate or shake. This dislodgement or removal of the accumulations of soot may be carried out while the heater is in use, and does not necessitate the handling or adjustment of any parts of the heater. In practice, the accumulations of carbon, soot, etc., may impair the efficiency of the heater, and it may be necessary to remove them when the heater is in operation.

The means 14 includes a deflector or baffle 45 to spread and direct the gases of combustion outwardly toward the corrugated collar 35 where they effectively mingle with the incoming air. The baffle 45 is centrally disposed within the corrugated collar 35 and is preferably conical in shape. In accordance with the invention, the deflector or baffle 45 is of less diameter than the collar 35 so that its periphery is spaced from the collar to provide an annular space S. An upstanding rim 70 is provided at the periphery of the baffle to lend rigidity to the baffle. The annular space S, together with the inner passages 38 of the corrugated collar 35, pass the heated gases of combustion upwardly from the fuel container 10 to the combustion chamber 13. Being conical, the baffle 45 is not easily warped and does not accumulate or gather soot, etc. Further, the conical baffle 45 is effective in promoting the efficient mixing of air with the gases of combustion. The air passing substantially horizontally inward through the slots 41 and corrugations, is deflected upward and inward toward a central

point causing an effective admixture of air with the combustion gases and a spiralled or swirling flame.

In the specific construction illustrated in the drawings, the baffle 45 is supported by spaced outwardly projecting extensions or arms 46 which pass outwardly through certain of the spaced slots 41. The lower edges of the arms 46 rest on the lower ends of the slots 41 to support the baffle 45 on the corrugated collar 35. The lower end of the main stack 12 rests on the spaced arms 46. A downwardly and outwardly inclined flange or lip 47 is provided on the lower end of the main stack 12 to provide an effective water shed and to seat on the bevelled outer ends of the arms 46. With the assembly of parts just described, the baffle 45, the corrugated collar 35 and the main stack 12 may each be easily and quickly removed or dismantled in the order named. It is to be noted that the assembly does not employ or necessitate bolts, screws, or like parts.

In the embodiment of the invention illustrated in Fig. 6 of the drawings, the air inlet means 11^b includes a rigid or fixed air baffle 27^a. The air deflector or baffle 27^a projects downwardly from the upstanding flange 22^a and extends to a point at or adjacent the bottom 15^a of the fuel container. The baffle 27^a is channel shaped in transverse cross section. The flanges or wings 80 which are on the outer side of the baffle 27^a are preferably widest at the upper end of the baffle. The other elements of the heater may be similar to or identical with those described above. The operation of the means 11^b is similar to that of the means 11. The incoming air is deflected downwardly and inwardly by the baffle 27^a so that it is spread against the surface of the burning fuel F and is prevented from prematurely rushing or passing upwardly out of the fuel container.

It is believed that the operation of the heater provided by this invention will be readily understood from the foregoing detailed description. The fuel F burns within the container 10 and the gases of combustion pass upwardly from the container 10 through the collar 17. Upon striking the baffle 45 the heated gases are spread outwardly toward the corrugated collar 35 and pass upwardly through the annular space S and the passages 38. The corrugated tube or collar 35 becomes heated from this action and presents a large outer surface which effectively heats the air passing upwardly through the passages 37. The air admitted through the passages 37, which might be termed the "auxiliary air," is pre-heated and expanded before reaching the combustion chamber proper, so that it effectively supports the combustion of the gases within the chamber. The air is free to pass into the chamber 13 in all directions as the V shaped cuts 40 and the slots 41 provide for the horizontal inward movement of the air while the passages 37 pass the air upwardly. In practice, the burner is capable of handling or burning a low grade hydro-carbon liquid fuel and produces a great heat with little or no smoke. After a period of use, accumulations of soot, carbon, etc., may collect on the corrugated collar 35 and the parts immediately adjacent. These accumulations may interfere with the admission of air into the combustion chamber 13 and thus impair the efficient operation of the heater. When this occurs the soot may be readily dislodged by tapping or lightly striking the corrugated collar 35 with a stick or other object. This may be done while the heater is in use and

hot, and causes the corrugated member 35 to vibrate or shake so that the soot, etc., falls from it. The burner may be constructed almost entirely of sheet metal and embodies only simple inexpensive parts. The various main or principal parts of the heater are assembled without the use of bolts or screws, and the heater may be taken apart without the use of tools.

Having described only typical preferred forms 10 of my invention, I do not wish to limit myself to the specific details set forth, but wish to reserve to myself any changes or variations that may appear to those skilled in the art or fall within the scope of the following claims:

15 Having described my invention, I claim:

1. An orchard heater of the character described including, a fuel container having an outlet for gases of combustion, a stack of greater diameter than said outlet spaced above the outlet, a longitudinally corrugated tubular collar receiving the gases from the outlet and extending into the lower end of the stack, said collar being provided with longitudinal slots in the upper end portion thereof, a baffle within the collar, and arms on 25 the baffle extending through the spaced slots and in supporting engagement with the lower end of the stack.

2. An orchard heater including, a fuel container, a stack for receiving gases of combustion from the container, said container having an air inlet, an air baffle spaced inward from the inlet and having its upper end pivoted to the container, and a float on the lower end of the air baffle for supporting it on the fuel.

3. An orchard heater comprising in combination, a fuel container having a gas outlet at its top, a stack arranged above said outlet and of greater cross sectional area than the outlet, a vertically corrugated collar interposed between 40 the outlet and the lower end of the stack, said collar having air openings formed therein to admit air into the stack, and a baffle arranged within the collar and spaced therefrom to deflect the gases rising upwardly from the outlet and 45 distribute said gases to the annular space formed between the collar and the baffle.

4. An orchard heater comprising in combination, a fuel container having an outlet neck at its top for the discharge of gases generated in the container, a stack of greater cross sectional area than the outlet neck arranged above said neck, a vertically corrugated collar interposed between the outlet neck and the lower end of the stack to receive the gases discharged through the neck and 50 to admit air to the stack, a baffle arranged within the collar and spaced therefrom to provide an annular passage for the discharge of the gases deflected outwardly by the baffle, and supporting arms for the baffle extending radially therefrom through the corrugated collar.

5. An orchard heater comprising in combination, a fuel container having an outlet neck at its top for the discharge of gases generated in the container, a stack of greater cross sectional area than the outlet neck arranged above said neck, a vertically corrugated collar interposed between the outlet neck and the lower end of the stack to receive the gases discharged through the neck and to admit air to the stack, a baffle arranged 55 within the collar and spaced therefrom to provide an annular passage for the discharge of the gases deflected outwardly by the baffle, and supporting arms for the baffle extending radially therefrom through the corrugated collar, the outer ends of the arms supporting said stack.

6. An orchard heater comprising in combination, a fuel container having an outlet neck at its top for the discharge of gases generated in the container, a stack of greater cross sectional area than the outlet neck arranged above said neck, a vertically corrugated collar interposed between the outlet neck and the lower end of the stack to receive the gases discharged through the neck and to admit air to the stack, a baffle arranged 5 within the collar and spaced therefrom to provide an annular passage for the discharge of the gases deflected outwardly by the baffle, and supporting arms for the baffle extending radially therefrom through the corrugated collar, the outer ends of the arms being bevelled, and a downwardly and outwardly inclined flange formed on the lower edge of the stack resting upon the bevelled outer ends of the arms.

7. An orchard heater including a fuel container having a gas outlet neck at its top, a vertically corrugated collar on the gas outlet neck, a combustion chamber having its lower portion supported by and surrounding the collar, a gas deflector arranged within the collar and spaced therefrom, the upper end of the collar having 25 V-shaped air openings, the upper end portion of the collar having additional air slots extending downwardly from the apices of the V-shaped openings to a point adjacent the deflector.

8. An orchard heater including a fuel container having a gas outlet neck at its top, a vertically corrugated collar on the gas outlet neck, a combustion chamber having its lower portion supported by and surrounding the collar, a gas deflector arranged within the collar and spaced 30 therefrom, the upper end of the collar having V-shaped air openings, the upper end portion of the collar having additional air slots extending downwardly from the apices of the V-shaped openings to a point adjacent the deflector, and 40 arms extending radially from the deflector through the slots to rest on the lower ends of said slots to support the deflector.

9. An orchard heater including a fuel container having a gas outlet neck at its top, a vertically corrugated collar on the gas outlet neck, a combustion chamber having its lower portion supported by and surrounding the collar, a gas deflector arranged within the collar and spaced 45 therefrom, the upper end of the collar having V-shaped air openings, the upper end portion of the collar having additional air slots extending downwardly from the apices of the V-shaped openings to a point adjacent the deflector, and 50 arms extending radially from the deflector through the slots to rest on the lower ends of said slots to support the deflector, the outer ends of said arms supporting the combustion chamber.

10. An orchard heater including a fuel container having an outlet neck at its upper end for 60 the discharge of gases generated in said container, a vertically corrugated collar encircling the neck and projecting thereabove, a stack encircling the upper portion of the corrugated collar, said corrugations forming a series of inner gas receiving 65 passages, and a series of outer air receiving passages to deliver air to the stack, the lower ends of the gas receiving passages being closed.

11. An orchard heater including a fuel container having an outlet neck at its upper end for 70 the discharge of gases generated in said container, a vertically corrugated collar encircling the neck and projecting thereabove, a stack encircling the upper portion of the corrugated collar, said corrugations forming a series of inner gas receiving 75 passages.

passages, and a series of outer air receiving passages to deliver air to the stack, the lower ends of the gas receiving passages being closed, said collar having vertical air slots extending downwardly from its upper edge, and a gas deflector arranged within the collar adjacent the lower ends of the vertical air slots, the deflector being spaced from the collar.

12. A heater of the character described including a fuel container having an outlet for

gases generated in said container, a stack above the outlet, a longitudinally corrugated tubular collar receiving the gases from said outlet and extending into the lower end of the stack to pass the gases into the stack, and a baffle arranged in the collar for deflecting the gases outwardly against the collar, said collar being provided with openings in the upper portion thereof to admit air into the collar and stack.

HOWARD H. CHRISTENSEN. 10
